UNITED STATES PATENT OFFICE.

JENNIE AKIN, OF PINE BLUFF, ARKANSAS.

DESIGN FOR A TEACHER'S HOLDER FOR WRITING MATERIALS.

SPECIFICATION forming part of Design No. 28,416, dated March 29, 1898.

Application filed February 28, 1898. Serial No. 672,100. Term of patent 14 years.

To all whom it may concern:

Be it known that I, JENNIE AKIN, a citizen of the United States, residing at Pine Bluff, in the county of Jefferson and State of Arkansas, have invented a new and original Design for a Teacher's Holder for Writing Materials, of which the following is a specification.

This invention relates to a new and original design for a teacher's holder for writing materials; and it has for its object to provide a design of this character that shall be both useful and ornamental.

The leading feature of the design resides in a rectangular tray having a flat bottom, double upright sides, each provided between the spaced walls thereof with a continuous rectangular series of open vertical boxes or compartments of a substantial square shape, and a central transverse partition extending upwardly from the flat bottom and provided at the upper edge thereof with a segmental handhold.

A minor feature of the design resides in the tray having therein separate rectangular boxes located, respectively, at opposite sides of the central transverse partition.

In the drawings, Figure 1 is a perspective view of a teacher's holder for writing materials embodying the herein-described design. Fig. 2 is a top plan view thereof.

Referring particularly to the drawings, the numeral 1 designates a rectangular tray hav-

ing a flat rectangular bottom 2, from the edges of which project upwardly-extending double sides 3, each of which double sides has an inner and an outer wall 4 and 5, respectively, and in the space between these walls 4 and 5 are fitted a plurality of regularly-spaced vertical partition-strips 6, which form therebetween a continuous rectangular series of open vertical boxes or compartments 7 of a substantial square form.

At a central point within the tray is arranged a transverse partition-board 8, extending the full width of the interior of the tray and projecting upwardly from the flat bottom thereof, said transverse partition-board being provided at its upper edge with a segmental handhold 8^a.

The design is completed by arranging within the tray, in corners thereof, rectangular boxes 9 and 10, located, respectively, in the compartments at opposite sides of the central partition 8.

What I claim is—

The design for a teacher's holder for writing materials, herein shown and described.

In testimony that I claim the foregoing as my own I have hereto affixed my signature in the presence of two witnesses.

JENNIE AKIN.
